TANK-FILLING NOZZLE WITH GAUGE

Grosvenor M. Cross, Beaver Bay, Minn.

Application October 10, 1932, Serial No. 636,974

3 Claims. (Cl. 226—66)

This invention relates to filling nozzles for tanks and the principal object of the invention is to provide a tank-filling nozzle with mechanism including a gauge operable to indicate when the liquid in the tank has reached a predetermined level.

More specifically the invention comprises a nozzle for the hose employed at gasoline filling stations, and the like, having a conduit provided with a gauge through which liquid from the tank 10 is caused to flow by suction produced by the flow of liquid through the nozzle into the tank.

A further object of the invention is to provide a nozzle of the character described which will be of rugged construction, practically immune to 15 injury in use, and which can be cheaply constructed.

These and other objects and features of the invention will more fully appear from the following description and the accompanying drawing and 20 will be particularly pointed out in the claims.

In the drawing:

Fig. 1 is a vertical longitudinal sectional view of a preferred form of nozzle embodying the invention;

25 Fig. 2 is a transverse sectional view on line 2—2 Fig. 1; and,

Fig. 3 is a transverse sectional view on line 3—3 Fig. 1.

The drawing illustrating the preferred embodiment of the invention shows only the nozzle through which liquid is delivered from a suitable supply to a tank, or other receptacle, it being understood that the nozzle may be secured to a preferably flexible hose leading from the supply 35 with a shut-off valve conveniently located in proximity to the nozzle to enable the flow of liquid to be quickly permitted or shut off.

The liquid may be supplied to the nozzle from the source of supply either by a pump or by a 40 reservoir located at such height as to give a substantial head to the column of liquid entering the nozzle. The nozzle comprises a body portion 1, preferably of tubular form, having at its upper end a screw threaded nipple 2 by means of which 45 it may be attached to the casing of a shut-off valve of any desirable construction such as that conventionally illustrated in Fig. 1, or to a hose with means for cutting off the flow of liquid there-through, and at its opposite end with a preferably 50 curved portion 3 adapted to be inserted through the usual filling aperture in the tank.

The nozzle may be made of any suitable material, such as brass, steel, or the like, and is provided with a main longitudinally extending passage 4 having at a distance from the discharge

end, and preferably in proximity to the inlet end, a constricted portion formed by oppositely disposed conoidal converging walls 5 and 6 merging into a narrow throat 7 and providing a Venturi-tube operable to increase the velocity of 60 the liquid as it passes through the throat 7 of the passage. The nozzle also is provided with a longitudinally extending passage of relatively small cross sectional area as compared with the cross sectional area of the main passage and 65 which is provided with an open lower end in proximity to the discharge end of the nozzle and communicates at its opposite end with the throat 7 to provide a suction passage through which liquid from the tank will be drawn by inspiration produced by the flow of the fluid through the Venturi-tube upon immersion of the open lower end of the suction conduit by the liquid in the tank. The 70 wall of the suction conduit is provided with transparent means enabling observation to be made of 75 the flow of liquid in the suction passage when induced by the flow of liquid through the Venturi-tube.

In the preferred construction illustrated herein in the body of the nozzle, which desirably is of 80 substantially circular cross section and somewhat tapered from the upper end to the lower end, is provided with a longitudinally extending hollow rib 8, the passage in which may be conveniently constructed by drilling a bore 9 longitudinally 85 of the main portion of the rib and by similarly drilling a communicating bore 10 through the portion of the rib which extends at an angle to the main portion and closing the entrance for the drill into the wall of the rib in proximity to the 90 junction of the bores by a suitable plug 11. Desirably a certain portion or portions of the walls of the rib are omitted for a short distance and the passage through the rib enlarged to provide 95 a chamber 12 for a gauge glass at some convenient portion of the suction passage, preferably in proximity to the inlet end of the nozzle, with a portion 13 of the wall forming a bridge over the chamber 12 which will effectively protect the gauge glass against injury. In order to mount 100 the gauge glass in the rib, the rib is counterbored from the upper end sufficiently to receive a cylindrical gauge glass 14 and a washer 15 interposed between the end of the gauge glass and the shoulder of the counterbore.

The end portion 16 of the rib beyond the bridge 13 is again counterbored and screw threaded to receive a plug 17 having an angular head 18 by means of which it may be screwed into place. A washer 19 is interposed between the end of the 110

plug and the other end of the gauge glass to provide a tight joint.

Suitable means are provided for establishing communication between the passage in the rib 5 and the throat 7 of the Venturi-tube. In the preferred construction such a passage 20 is produced by drilling obliquely from the bore in the end portion 16 of the rib through the body of the nozzle into communication with the throat 7 of 10 the venturi.

In the particular construction illustrated herein in the plug 17 is provided with an axial bore 21 which communicates with an annular peripheral recess 22 in the plug 17 which in turn communicates with the passage 20. Suitable means desirably are provided for determining the depth into which the discharge end of the nozzle is inserted into the tank, so that when the liquid in 15 the tank has reached a predetermined level, which 20 will submerge the open end of the suction conduit, the flow of liquid will be induced in the suction conduit by the flow of liquid through the Venturi-tube. Any suitable means may be provided for accomplishing this purpose. In the preferred 25 construction the lower end of the rib 8 terminates slightly short of the end of the nozzle and is provided with an upwardly extending boss 23 having an abrupt shoulder 24 which may be raised into engagement with the under surface of a suitable 30 portion of the upper wall of the tank. The rib may, however, be provided with a plurality of shouldered stops of like character which may be placed into engagement with an upper or lower surface of a portion of the top or other wall of 35 the tank in such manner as to position the end of the nozzle at such predetermined distance from the bottom of the tank as may be required to determine the desired depth of liquid in the tank.

In the operation of the particular embodiment 40 of the invention disclosed herein, the end of the nozzle will be inserted through the filling aperture in the tank and the nozzle thereupon raised until the shoulder 24 engages the under face of the upper wall of the tank. Liquid will then 45 be admitted to the nozzle through the usual shut-off valve and will continue to flow from the nozzle into the tank. As the liquid level in the tank nears the top, waves, splashes, bubbles, thereof will reach the lower end of the suction passage 10 and these will pass upwardly through the suction conduit 9 and gauge glass 14, thereby giving a clear indication of the approach of the liquid level to the top of the tank. As the level 50 grows higher the number of splashes reaching the opening will grow greater and more and more bubbles of liquid will pass through the gauge glass until finally as the tank is full clear liquid 55 will be drawn through showing clearly that the tank is filled, thus enabling the operator to shut off delivery of the liquid into the tank in ample time to prevent the tank from running over and the wastage of gasoline, or other liquid, being delivered to the tank.

Obviously such a nozzle can be readily and 60 economically constructed and by reason of the fact that the nozzle is of a rigid construction and the gauge glass effectively protected by the rib 13, the nozzle will last indefinitely notwithstanding the hard usage to which it may be subjected.

It will be understood that the particular embodiment of the invention disclosed herein is of an illustrative character and is not restrictive of the scope and meaning of the following claims.

Having thus described the invention, what is claimed as new, and desired to be secured by Letters Patent, is:

1. A tank-filling nozzle comprising a tubular body having a main passage for liquid extending longitudinally thereof and provided with a constricted portion located at a distance from the discharge end of said nozzle forming a Venturi-tube, a rib extending longitudinally of said body and bored longitudinally to provide a passage of small cross-sectional area relatively to that of said main passage, the upper end of said rib having a countersunk bore and the walls of said rib adjacent said bore being provided with an aperture, a gauge glass mounted in the countersunk portion of said bore and protected from injury by the remainder of the wall of said rib, said body having a passageway establishing communication between the chamber of said gauge glass and said Venturi-tube, and means for sealing the upper end of said countersunk bore. 100

2. A tank-filling nozzle comprising a tubular body having a straight section and an end section extending at an angle to the axis thereof, and having a main passage for liquid extending longitudinally of said sections with a constricted portion of said straight section forming a Venturi-tube, a rib extending longitudinally of said section terminating in proximity to the discharge end of said nozzle and having an outwardly extending projection presenting a shoulder adapted 110 to engage the under face of the inner wall of the tank, said rib having longitudinally extending intersecting bores open at the lower end of said rib and said body having a bore establishing communication between the bore of said rib and 115 said Venturi-tube, said rib having a counterbore extending inwardly from the upper end of said rib, a gauge glass mounted in said counterbore, a screw threaded plug mounted in the upper end of said rib having an axial bore communicating 120 with the chamber of said gauge glass and an annular recess communicating with the bore of said plug thereby establishing communication between said Venturi-tube and the bores of said rib to provide a suction conduit, and the wall of said 125 rib having a lateral aperture permitting observation of said gauge glass.

3. A tank filling nozzle presenting a liquid discharge passage extending longitudinally therethrough with a section of said passage forming a Venturi-tube, the said nozzle also having a suction conduit extending longitudinally thereof with one end opening into the throat of the Venturi-tube and the other end opening in proximity to the discharge end of the nozzle, the wall of 130 said suction conduit at a substantial distance from the discharge end having a transparent exterior portion through which liquid flow in the conduit is observable, whereby when the level of the liquid discharge by the nozzle into the tank 140 reaches the open end of the suction conduit, an observable flow will be induced in the conduit by the action of the Venturi-tube. 135
